E. BIGNELL.
MEANS FOR FORMING UNDERGROUND FOOTINGS FOR PILES AND CAISSENS.
APPLICATION FILED AUG. 26, 1912.

1,084,063.

Patented Jan. 13, 1914.

UNITED STATES PATENT OFFICE.

EDWARD BIGNELL, OF LINCOLN, NEBRASKA.

MEANS FOR FORMING UNDERGROUND FOOTINGS FOR PILES AND CAISSENS.

1,084,063.

Specification of Letters Patent. Patented Jan. 13, 1914.

Application filed August 26, 1912. Serial No. 716,968.

To all whom it may concern:

Be it known that I, EDWARD BIGNELL, a citizen of the United States, residing at Lincoln, in the county of Lancaster and State of Nebraska, have invented certain new and useful Improvements in Means for Forming Underground Footings for Piles and Caissons, of which the following is a specification.

10 This invention relates to means for forming underground seats or foundations for piers, caissons and piling generally.

Where piles, caissons or piers are sunk to a depth insufficient to reach a solid foundation, it is obvious that the formation of concrete or cement foundations below their bottoms and upon which they would be supported, would be an advantage.

While the practice of this invention would 20 be useful to form foundations for piers, sheet piling, caissons or concrete piles generally, it is particularly adapted for and is illustrated and described in connection with U. S. Letters Patent No. 1,026,144, for concrete piling, issued to Edward Bignell, May 25 14, 1912.

The invention consists of the novel construction, combination and arrangement of parts as described herein and claimed, and 30 as illustrated in the accompanying drawing, wherein,—

Figure 1 is a side elevation of a concrete pile, the view being partly broken and in section. Fig. 2 is a view similar to that 25 shown in Fig. 1, the pipe for conducting water and the nozzle being removed, and the parts arranged for the use of compressed air. Fig. 3 is a view, on a reduced scale, of the same piling illustrated in Figs. 1 and 2, 40 a piston being shown as a means for pressing the cement or concrete, to cause it to move below the pile.

Referring now to the drawing for a more 45 particular description, numeral 4 indicates the body of a concrete pile, having any desired length, width or thickness, and formed with a longitudinal aperture 5, opening upon its top and bottom, and at 6 is indicated a housing-tube or interior lining for aperture 5. A conducting-pipe 7 may be disposed in tube 6, said pipe 7 having, at its upper end, a supply pipe 24, its lower end being provided with a nozzle 8 having a threaded connection *a* with collar 9, said 55 collar being embedded in and circumscribed by the concrete body of the pile. The lower

end of the conducting-pipe 7 has a threaded connection *b* with the boss or rim *c* of the nozzle, the threads of said nozzle being inclined reversely to the threads of the conducting-pipe. At 10 are indicated numerous, transverse perforations or discharge apertures opening upon the surface of the pile and communicating with the longitudinal aperture 5; and the water, under 60 pressure, may be discharged within aperture 5 through a supply pipe 11, and the water, thus under pressure, will finally be discharged through perforations 10. In practice, any desired number of apertures 65 5, pipes 7 and nozzles 8 may be employed, and the pile or caisson provided with the parts mentioned, may be sunk into the ground without the use of a pile driver, since the water, under pressure, which is 70 discharged through the nozzle, will remove the ground at and below the bottom of the pile, and the water which passes through perforations 10 will remove the ground and adhesions at the sides of said pile.

The parts thus explained are fully described and claimed in the Letters Patent above referred to, and are now mentioned simply for convenience, so that the present invention may be clearly described.

To provide the cement or concrete foundation, support or barrier 12 below the bottom of the pile 4, as shown in Figs. 2 and 3, after the pile has been sunk, certain means are employed to now be described.

At 13 (Fig. 2,) is indicated a screw-cap adapted to be threaded upon the upper end of sleeve 14, this sleeve projecting above the upper terminal of the conducting-pipe, said terminal thereby forming an annular ledge 95 21 opening upon aperture 5, below supply-pipe 19. An annular recess 22 is formed to open upon the upper end of the pile, and the threaded wall of the cap may be disposed therein for its mounting upon the sleeve.

At 15 are indicated reinforcing strips embedded within and disposed longitudinally of the pile. They are preferably of metal, and their lower terminals may be provided or formed as anchor-pins or heads 16 disposed to project below the lower end of said pile. After the pile has been sunk to a required depth, the conducting-pipe 7 and nozzle 8 are to be removed. Since this pipe and nozzle are reversely threaded, a rotation 105 of the conducting-pipe in one direction will cause a release of the nozzle from collar 9,

and therefore the pipe and nozzle may be conveniently removed. Before removal of this pipe the supply-pipe 24 and T-pipe coupling 23 should be removed. After the conducting-pipe and nozzle have been removed from the pile, any suitable tie-rods, metallic tie-strips, strands or cables 17 may be disposed within aperture 5. They may be supported in any suitable manner, as upon the ledge 21, and they project through the aperture 18 (Fig. 2) of collar 9 to be disposed below the pile. According to the arrangement of parts shown in Fig. 2, a mixture of concrete, cement or other similar material 15 may be deposited within aperture 5, cap 13 being temporarily removed for this purpose; and after cap 13 has been mounted upon sleeve 14, a force of steam, compressed air or other expansion element may be applied, the same being discharged within the upper end of the pile through supply-pipe 19, the concrete or mixture, by reason of the pressure thus provided, being moved downwardly through aperture 18 to form the 20 foundation 12, and members 17, if they are flexible, will be carried with the material or mixture, so that parts of these members will be disposed below the pile to form a part of the foundation. As soon as the concrete material or mixture becomes hardened, the foundation will prevent the pile from settling and will operate as a holding means to prevent any lateral movement of the pile. Members 16 and 17 will be invested by the 25 concrete material and will be operative to firmly connect the pile with the foundation. Aperture 18 provides the discharge port, and when the concrete or cement passes therethrough, it will move in directions of least resistance, and therefore it will generally form a wall to surround the pile as well as to form a seat below it. The effect of the forced movement of the mixture as described, will also cause apertures 10 to be filled, and in practice after the foundation 12 has been formed, the aperture 5 may be, and generally is, filled to form a solid pile.

Instead of employing air or steam to provide a required pressure for causing the 30 foundation to be formed, any other suitable means may be used, as the piston 20, shown in Fig. 3. By this arrangement, the mixture may be deposited in the upper end of longitudinal aperture 5, and after the piston 20 is 35 inserted and actuated, the mixture will move

through the discharge port 18, and will be deposited below the pile to form the desired concrete seat or foundation.

While I have described my invention in connection with concrete piles, I do not 40 limit myself in this respect, and it may be employed with equal advantage in forming seats or foundations for sheet-piling, caissons or similar structures.

The housing or lining 6 may be dispensed with if desired; however it is desirable as a bearing for sleeve 14, and provides a cylinder in which piston 20 may work; when said piston is employed.

It will be understood that by the terms 45 "cement" and "concrete" used herein, in describing the filler or mixture which is to be moved through the discharge port 18 by a pressure element to form the footing or foundation 12, is meant any desired plastic 50 mass or mixture, one ingredient of which should be hydraulic cement. The ordinary mixture of water, gravel or crushed rock, with sand and cement may be employed, but of course these ingredients and their proportions may be changed; and any mixture may be used which is plastic at the time it is moved, and which afterward becomes hardened to form a rigid footing or support for the pile or caisson. 55

Having fully described my invention, what I claim and desire to secure by Letters Patent is,—

In a device of the character described, the combination with a body portion having a 60 centrally arranged bore, a sleeve located in said bore and terminating short of the top of said body portion, a collar surrounding the upper end of said sleeve, a cap mounted upon said collar, the upper end 65 of said sleeve forming an internal ledge within said bore and reinforcing members suspended from said ledge, said reinforcing members being sufficiently flexible to permit of their being carried through said 70 bore with a cementitious material and means for applying pressure to such cementitious material to cause it to travel through said bore.

In testimony whereof I have affixed my 75 signature in presence of two witnesses.

EDWARD BIGNELL.
